CLAIM

The ornamental design of a truck body rock shield, as shown and described.

DESCRIPTION

FIG. 1 is a perspective view of a truck body rock shield showing my new design, it being understood that the broken lines are for illustrative purposes only;
FIG. 2 is an enlarged front elevational view thereof;
FIG. 3 is a side elevational view of FIG. 2;
FIG. 4 is a side elevational view of FIG. 2 opposite to that shown in FIG. 3;
FIG. 5 is a top plan view of FIG. 2; and,
FIG. 6 is a bottom plan view of FIG. 2.

FIG. 1

FIG. 5

FIG. 2

FIG. 3

FIG. 4
